(57) **CLAIM**

The ornamental design for a wireless communication apparatus, as shown and described.

DESCRIPTION

FIG. 1 is a front view of a wireless communication apparatus including a body and a stand according to the present invention;

FIG. 2 is a rear view of the wireless communication apparatus;

FIG. 3 is a right side view of the wireless communication apparatus, the left side being a mirror image thereof;

FIG. 4 is a plan view of the wireless communication apparatus;

FIG. 5 is a bottom view of the wireless communication apparatus; and,

FIG. 6 is a perspective view of the wireless communication apparatus.

The broken lines shown throughout the views are for illustrative purposes only and form no part of the claimed design.
